DIVIDED SNACK TRAY

Willis A. Stageberg, Minneapolis, Minn., assignor, by mesne assignments, to Plastics, Inc., St. Paul, Minn., a corporation of Delaware

Filed July 27, 1967, Ser. No. 8,026

Term of patent 14 years

(Cl. D44—10)

FIGURE 4 is an end elevational view of the same showing the other end thereof;

I claim:

The ornamental design for a divided snack tray, as shown.
